UNITED STATES PATENT OFFICE.

CHARLES A. CHASE, OF CHICAGO, ILLINOIS

LAMP-SOCKET.

No. 845,754.

Specification of Letters Patent.

Patented March 5, 1907.

Application filed December 29, 1906. Serial No. 349,987.

To all whom it may concern:

Be it known that I, CHARLES A. CHASE, a citizen of the United States, residing at Chicago, in the county of Cook and State of Illinois, have invented a certain new and useful Improvement in Lamp-Sockets, of which the following is a specification.

My invention relates to electric-lamp sockets, particularly such as are intended for use in connection with signs.

It is illustrated in the accompanying drawing, wherein—

Figure 1 is a plan view of a portion of a sign-board with one socket in view. Fig. 2 is a section on the line 2 2 of Fig. 1. Fig. 3 is view of the bottom of the socket.

Like parts are indicated by the same letter in all the figures.

A is the sign-board, B the base of the socket, and C the socket proper. The base has the usual terminals B' B² with the securing and contacting rods B³ B⁴ B⁵. B³ and B⁵ are adapted to hold in position the internally and externally screw-threaded thin metal piece C' and to make connection between the same and the terminal B'. The bolt B⁴ holds in position the insulation-disk C² at the bottom of the socket-piece C' and also furnishes an exposed contact end B⁶ to engage the lamp when the latter is screwed into position, as hereinafter explained. There is a deep annular recess in the forward end of the base, as indicated at B⁷, to receive an inwardly-projecting annular flange C⁴ on the socket C. The parts B and C are opposed to each other by flat shoulders or surfaces and when in position are slightly separated, so as to give room between them for the board or sheet-piece A. The socket C is preferably corrugated on its outer surface, so that it can easily be screwed up tightly against the plate A to bring all the parts into position. It is also internally screw-threaded, so that it is screwed down upon and so as to inclose the socket-piece C'.

The parts can of course be varied and are to be taken as in a sense shown diagrammatically.

The use and operation of my invention are as follows: In sockets where the object is to expose the lamp to view as a conspicuous object—that is, particularly where lamps are utilized to form, for example, lettered signs—it is highly desirable to have the least possible part of the socket itself exposed to view. In

other words, my socket for the purposes for which it is used may be considered as a socket, part of which is exposed and part concealed. The making of such signs has become a very considerable industry and the public has become very critical and insists upon the least possible exposure of the socket, so that the lamp itself may attract all the attention of the observer. At the same time the underwriters or others who are clothed with the authority to determine what kind of apparatus should be used are insisting upon heavier and more solid sockets. This requirement in the sockets as heretofore used resulted in a very heavy socket-piece, and since under previous structures the socket-piece has been adapted to lie wholly on the socket side of the supporting board or sheet the result was a very heavy and unsatisfactory socket, and when a series of such sockets were arranged in a sign-board the result was highly unsatisfactory. To overcome these difficulties is the object of my invention. Broadly speaking, I accomplish that object by putting my socket portion on both sides of the board or projecting a portion of it through the board or sheet to a considerable extent or great depth. This gives me a heavy socket-piece, but a small portion of which necessarily lies on the exposed side of the supporting-plate. I have shown this socket as lying about half of it on the exposed side of the plate. It is obvious that by this invention I have divided the underwriters' requirements and dealt with each separately. In other words, to satisfy their requirement that the socket-piece be heavy I have extended and developed it on the back side of the plate, while to satisfy their requirement that there shall be an appreciable distance between the sheet and the metal piece C', I am permitted to use a socket C with the smallest permissible outer projection. The proportions of the parts as shown may be greatly varied.

I claim—

1. A supporting-body having a perforation, in combination with a lamp-receptacle comprising a back section of insulating material lying against one side of the supporting-body, an internally and externally screw-threaded socket secured to the back section, a front section of insulating material having an internal thread so as to screw onto the end of the socket and against such support-

ing-body, and a flange on the front section lying between the socket and the material of the supporting-body.

2. A supporting-body having a perforation, in combination with a lamp-receptacle comprising a back section of insulating material lying against one side of the supporting-body, an internally and externally screw-threaded socket secured to the back section, a front section of insulating material having an insulating-thread so as to screw onto the end of the socket and against such supporting-body, the back section being recessed, and a flange on the front section lying between the socket and the material of the supporting-body and extending into the recess in the back section.

3. A supporting-body having a perforation, in combination with a lamp-receptacle comprising a back section of insulating material lying wholly on one side of the supporting-body and against the same, a socket se-

cured to the back section, a front section of insulating material having a part lying against the front side of the supporting-body, and a flange extending between the supporting-body and the socket.

4. A supporting-body having a perforation, in combination with a lamp-receptacle comprising a back section of insulating material lying wholly on one side of the supporting-body and against the same, said back section being recessed centrally, a socket secured within the recess so as to form an annular channel, a front section of insulating material having a part lying against the front side of the supporting-body, and a flange extending into the channel between the supporting-body and the socket.

CHARLES A. CHASE.
